UNITED STATES PATENT OFFICE

GEORGE C. SNYDER, OF NEW YORK, N. Y., ASSIGNOR TO KAEELMA MANUFACTURING COMPANY, INC., OF NEW YORK, N. Y., A CORPORATION OF NEW YORK

BAG OR ENVELOPE

Application filed November 28, 1924. Serial No. 752,667.

This invention relates to handled bags or envelopes of the general type shown and described in my prior application, filed October 17, 1923, Serial No. 668,992.

- 5 One of the objects of the present invention is to provide a bag or envelope which has a handle, that is operable on the closure flap of the bag and is adapted to be extended or moved through the wall which supports the flap in order to close the flap, with means for automatically and mutually locking or binding the handle with the two walls of the bag when the flap is closed, the locking or binding action being preferably of 10 such nature as to create a resistance which is just sufficient to hold the mouth of the bag closed against any tendency of the contents of the bag to open its mouth when the bag is overfilled.
- 20 Another object is to so simplify and construct the handle that when the flap of the bag is closed, a positive outward pull on the flap will retract the handle and automatically overcome the locking or binding action, 25 so that the flap of the bag may be opened with ease, thus avoiding the necessity of any other manipulation than a mere positive pull on the said flap, and therefore locking and unlocking the bag may be repeated.
- 30 With these and other objects in view, the invention consists of certain features of construction and combinations of parts to be hereinafter described and then claimed with reference to the accompanying drawings illustrating several embodiments of the invention, and in which—

Fig. 1 is an elevation of a bag with the closure flap open, and showing one embodiment of the invention;

40 Fig. 2 is a section on the line II—II, Fig. 1; Fig. 3 is an elevation of the bag showing the closure flap closed and the handle extending above the fold-line of the flap, and also showing how the interlock between the handle and the two walls of the bag is established.

Fig. 4 is a section on the line IV—IV, Fig. 3;

50 Figs. 5 and 6 are enlarged detail views, respectively in section and sectional plan, on

line VI—VI, Fig. 5 showing how the handle is releasable;

Fig. 7 is an elevation of a modified handle; Fig. 8 is a transverse section on the line

VIII—VIII, Fig. 7;

Fig. 9 is an elevation of another modified form of handle; and

Fig. 10 is a transverse section on the line X—X, Fig. 9.

Referring to Figs. 1 and 2, the bag or envelope has walls 10, 11, and a closure flap 12 which is foldable at fold-line 13. A handle 14 has at one end an attaching member 15 which is preferably secured at the outer part thereof to the inner surface of the outer end 60 of the flap 12 as by gum, paste or otherwise. The handle is preferably narrower than the attaching member 15, and near its terminal it may be provided with a finger hole 16. The bag body may be composed of 70 any suitable flexible material such as thin paper or cloth, while the handle 14 and its attaching member 15 are preferably composed of one piece of flat and stiffer material, such as paper-board for example. 75

The ends of the attaching member 15 are adapted to form shoulders at 15^a towards the handle proper, and adjacent to said shoulders the base of the handle is somewhat wider than the handle itself so as to provide lateral base portions 17, for a purpose to be mentioned. The handle has shoulders or small projecting portions 18 which project away from the plane of the handle and are located at its base, on the other side of 80 a straight transverse line which is coincident with the edges of the shoulders 15^a. These shoulders 18 are preferably of approximate V-form, with the apices pointed towards the terminal of the handle and with their substantial squared shoulders-proper 18^a at the line coincident with the shoulders 15^a. These shoulders-proper 18^a are preferably at a right angle to the backs of the shoulders 18 so as to be at an obtuse angle to the flap 12 and 90 attaching member 15.

95 Preferably these tapering or V-shaped shoulders are formed from the material of the handle itself by striking them out of the said material by means of punches in the act 100

of forming the handle, so that when one surface of the handle is attached to the flap of the envelope the shoulders 18 will project slightly away from the other surface of the handle.

5 The terminal 19 of the handle 14 is preferably located in a transverse slit or opening 20 in the wall 11 so as to normally protrude slightly through said slit for engagement by 10 a person's fingers. The back wall 10 of the bag is provided with a cut-out 21 preferably having square corners and parallel edges 22 at each end. It will be noticed that the slit 20 is of approximately the same length as 15 the cut-out 21 and that it is practically coincident with the long transverse edge of the cut-out, for the purpose of obtaining, as is preferably desired, the closest locking co-operation between the handle and the two 20 walls of the bag when the flap is closed.

Referring to Figs. 3 and 4, the bag is shown as closed, that is to say, it has been closed by a person who preferably takes hold of the terminal 19 of the handle or flap closing 25 means, and pulls thereon away from the bag and outwardly away from the fold-line 13 of the flap, so that the handle will extend away from the bag when the flap is closed.

It will more clearly be observed from the 30 section, Fig. 4, just how the interlock or binding action is established between the handle and the two walls of the bag. When the flap is being pulled shut, the wider base portion of the handle, at 17, will be pulled snug into the 35 slit 20 and said slit practically sealed closed, and the shoulders 15^a on the handle, which are preferably free of adhesive and are not themselves directly secured to the flap, will be brought into binding relation with the 40 portions 22 of the back wall 10, at one side of the slit 20, while the shoulders 18 will be pulled through the slit and their shoulders-proper 18^a, will establish an interlock, at the other side of the slit, between the front wall 45 11 and the protruding handle. This action results in a mutual interlock or binding action between the two walls of the bag and the handle, the binding action taking place at opposite sides of the slit 20, or in other words 50 at the opposite side walls of the bag over which the flap is closed. This binding action preferably takes place in the vicinity of the extreme ends of the slit. When the shoulders-proper, 18^a, are at the approximate 55 angle as shown they will be given a snugger and better binding contact with the lower edge of slit 18, as is obvious.

It is preferable to apply a reinforcing patch 23 to the slitted wall of the bag so as 60 to strengthen the bag at that portion.

It will be clear to those skilled in the art that as the preferred material of the bag or envelope is thin paper such as bags of this general type are usually composed, the bag 65 is so thin that the sectional views are some-

what exaggerated. That is to say, in practice the portions of the wall 10, 11 which are located at opposite sides of the slit 20 and the portions of the patch 23, as well as other involved portions of the bag, lie substantially in the planes which such parts assume in a thin, flat bag.

If the bag or envelope is overfilled, a considerable bulging thereof is produced with a tendency to draw the handle out of locking 75 engagement with the bag and to push the bag wall 10 away from under the flap 12. The mutual interlock before described controls the contents of the bag substantially within the limits of the strength of the material of the bag and the contents do not control the interlock, except to cause a more effective binding or locking action.

To remove the contents of the bag a person takes hold of the edge of the flap at 85 handle attaching member 15 and pulls outwardly thereon to bring the handle to about the position shown in Figs. 5 and 6, when by a more or less vigorous pull the inclined shoulders 18^a are closed to force the slit open 90 so that the handle may be readily withdrawn and the flap opened. This is all done during one swinging or opening movement of the hand which takes hold of the flap.

The means for establishing the described 95 interlocking or binding action are susceptible of more or less modification. Figs. 7 and 8 illustrate a modified form of handle 24 which is provided at its base with short transverse slits 25, while the lateral portions 100 of the base such as in the preferred form, may be formed up into slight shoulders or projections 26 of somewhat similar shape to the V-shape or tapering shoulders 18 before described. Or, a handle 27 may be provided 105 with instead of having portions punched out and set in raised position thereon may be entirely flat including its attaching member, as shown in Figs. 9 and 10. In this case, the handle is provided with short transverse 110 slits 28 at the lateral base portions 29 and when the flap of the bag has been closed the portions 29 may be turned back towards each other by the fingers of a person to form shoulders, which would provide very reliable but not strictly automatic locking means.

What I claim as new is:

1. In a bag or envelope, the combination of the bag body having a closure flap on one wall, automatic closing means adapted to be moved outwardly through the said wall and operable from the outer side of said wall to close the flap, and having means for automatically bearing on the other wall, and means for locking engaging said closing means with the 120 wall which supports the flap.

2. In a bag or envelope, the combination of the bag body having a closure flap on one wall, closing means adapted to be moved outwardly through the said wall and operable 125

on the flap to close it, and means for mutually and automatically locking the flap closing means and the two walls of the bag by movement of the flap from open to closed position.

5 3. In a bag or envelope, the combination of the bag body having a closure flap on one wall, said wall having an opening, a handle projecting outwardly through the said opening when the flap is open and operable on the 10 flap to close it, and means on the handle for acting at opposite sides of the opening to bind the two walls of the bag together when the flap is closed.

15 4. In a bag or envelope, the combination of the bag body having a closure flap, a flat handle of comparatively stiff material movable through the front wall and operable on the flap to close it, the handle extending outwardly beyond the fold-line of the flap when 20 the flap is closed, and locking means near the opposite edges of the handle for engaging the two walls and for mutually binding the two walls of the bag together when the flap is closed.

25 5. In a bag or envelope, the combination of the bag body having a closure flap, and a flat broad handle elongated longitudinally of the bag and of relatively stiff material operable on the flap to itself move the flap to closed position, and locking projections on the handle for engaging with the wall which supports the flap and for engaging and locking with the other wall.

30 6. A handle for bags or envelopes having means at one end for engagement by the fingers, and, near the other end cooperating means comprising opposed shoulders adapted to mutually bind the opposite walls of the bag between them such shoulders having a separation substantially equivalent to the thickness of such bag.

35 7. A handle for bags or envelopes having means at one end for engagement by the fingers, and, near the other end, separated shoulders cooperating to bind the opposite walls of the bag between them, two of such cooperating shoulders being located at each side of the handle and having a separation substantially equivalent to the thickness of such bag.

40 50 8. In a bag or envelope, a body portion having front and back walls, a closure flap, a handle secured to the closure flap and extending through the front wall, and means on the handle for automatically locking it with the front and back walls of the bag as the flap is closed.

45 60 9. In a bag or envelope, a body portion having front and back walls, a closure flap, a handle secured to the closure flap and extending through the front wall, and movable therethrough to close the flap, means on the handle to limit the movement of the handle through said front wall, and means for locking the handle with both walls of the bag 65 when the flap is closed.

10. In a bag or envelope, the combination of the bag body having a closure flap, a flat broad handle of comparatively stiff material operable on the flap to move it to closed position, and locking projections extending outwardly from one surface of the handle for mutually engaging and binding the two walls of the bag together when the flap is closed. 70

11. A handle for bags or envelopes, formed from comparatively stiff sheet material, and having means at one end for engagement by the fingers, and near the other end, preformed portions deflected outwardly from the plane of the sheet material to provide formed means for engaging an edge of a bag to which it may be applied. 75
